UNITED STATES PATENT OFFICE

PAUL G. KAISER, OF CHICAGO, ILLINOIS

BOILER

Application filed March 17, 1928. Serial No. 262,371.

This invention relates to improvements in boilers and more particularly to improvements in combined water-tube and fire-tube boilers.

The main object of my invention is to increase the capacity of a fire-tube boiler, which end I effect by the use of water tubes disposed along the side walls of the combustion chamber.

Another object of my invention is to increase the longitudinal distribution of the water in the fire-tube shell to be drawn into the water tubes.

Another object of my invention is to amplify and increase the circulation of water in the boiler.

A further object of my invention is to safeguard and protect the boiler shell from injury, should a leak occur in a water tube.

I use a boiler construction comprising a fire-tube boiler shell having co-ordinated water tubes lining the sides of the combustion chamber of the boiler which are adapted to take in water from the boiler shell, and provide means to take in water from this shell at a point where the maximum longitudinal distribution of the downflowing water is available but at a point high enough to prevent the draining of the boiler, should a leak occur in one of the water tubes or their headers. I also provide means to return the heated, rising water and steam from the water tubes to the boiler shell at a point near the water level in the boiler.

These and further features and advantages of my invention are set forth in the following detailed description and accompanying drawings, in which:

Figure 1 is a longitudinal, vertical side elevation of a boiler embodying the features of my invention, shown partly in section to illustrate certain details more clearly.

Figure 2 is a front elevation of this boiler, partly in section.

Figure 3 is an enlarged, fragmentary, vertical cross-section of a part of the boiler shell illustrating certain details of the construction.

Figure 4 is a front elevation, partly in sec-

tion, of another form of boiler embodying the features of my invention.

Figure 5 is a longitudinal, vertical sectional view, taken on the line 5—5 of Figure 4, with the layer of refractory material, shown in Figure 4, omitted for clearness.

Figure 6 is a side elevation, partly in longitudinal section, of still another type of boiler embodying the features of my invention.

Figure 7 is a vertical, cross-sectional view of this type of boiler taken on the line 7—7 of Figure 6.

A fire-tube boiler shell 10 of well-known construction (Figure 1) is supported by suspension brackets 11 hung from I-beams 12, which are supported by uprights 13. A combustion chamber 15 (here shown as adapted to powdered coal) is formed under the boiler shell 10 and is suitably enclosed by a front brick wall 14, a rear brick wall 16 and suitable side walls 22 of refractory material. The combustion gases have their outlet at the rear end of the combustion chamber into a fire chamber 17, whence they pass forwardly through fire tubes 18 of the boiler shell 10 into a smoke-box 19 at the front end of the boiler, and they are thence exhausted upwardly through the smokestack 20. The boiler shell 10 is provided at one end of its lower surface with a blow-off pipe 21.

The above description outlines a boiler of a fire-tube type well known in the art. I now provide a series of parallel, vertically disposed water tubes 25 which are spaced relatively close together, substantially along the length of the opposing walls of the combustion chamber 15. These water tubes, at each side, are connected at their lower ends by a horizontally disposed lower header manifold 26 and are connected by a similarly disposed upper header manifold 27 at their upper ends. The upper headers 27 are suitably supported by brackets 28 which are secured to the sides of the boiler shell 10 and the lower headers 26 may be supported in any suitable manner at the lower portions of the combustion chamber.

Referring now to Figure 2 and to the arrangement of the fire tubes 18 in the boiler

shell 10, it will be noted that the fire tubes are arranged in four groups of vertical tiers spaced to form a central passage 29 to facilitate the upward flow of the heated, rising water, between the two inner groups. Substantially midway between the respective outer tiers of fire tubes 18 and passage 29, are other vertical passages 30 which extend transversely throughout substantially the length of the boiler. A pair of circulating plates 31 is vertically disposed in each of these paths 30, as shown in Figures 2 and 3. These circulating plates greatly facilitate the circulation of the water and add to the productive capacity of the boiler because they confine the major portion of the downwardly-flowing water to the relatively cool spaces 30 between these plates 31 which shield said spaces from the heat of the adjacent fire tubes 18. This circulating plate construction is more fully described in my co-pending application, Serial No. 473, filed January 5, 1925.

The largest volume and fastest moving columns of downflowing, cooling water in the boiler shell 10 will be along these paths 30 between the baffle plates 31.

Intake pipes 33 are mounted at opposite ends of the boiler in each of the passages 30. These intake pipes 33 extend upwardly between the circulating plates 31 to substantially the horizontal plane of the axis of the boiler. They are connected at their lower ends with the water tubes 34 which, in turn, are connected to the opposite ends of the lower header manifolds 26 located on either side of the combustion chamber.

The downward-flowing water in the passages 30 of the boiler shell 10 is conducted through the intake pipes 33 and 34 to the lower header manifolds 26 where it enters the water tubes 25 which line the sides of the combustion chamber 15 of the boiler.

As the water in the tubes 25 becomes heated, it rises in the tubes to the upper header manifolds 27, whence it is discharged into the boiler 10 at a point near the level of the water in the boiler, indicated by the numeral 32, through discharge pipes 35.

The downwardly-flowing water in the passages 30 between the circulating plates 31 is drawn into the intake pipes 33 at a point near the center of the boiler 10 after the water has flowed over the tops of the circulating plates 31 and down to the center of the boiler. The water taken in by the intake pipes 33 at this point will be drawn not only from the water directly above the intake 33 but from the water between the plates 31 distributed some distance longitudinally away from the intake pipes 33, as illustrated by the arrows in Figs. 5 and 6. The water to be taken in by the pipes 33 is distributed transversely and longitudinally between the circulating plates 31 and both forward and rearward of the intake pipe 33. This enables a larger volume of the

cooling downflowing water in the boiler to be placed in circulation in the water tubes, thus tending to amplify and increase the circulation of the water in the boiler.

Another important feature in the locating of the top of the intake pipe 33 near the horizontal plane of the axis of the boiler is the safety factor which insures against complete draining of the boiler shell 10, should a leak occur in one of the water tubes 25. In the event of such a leak, the water would only be drained down to the center line of the boiler; that is, to the tops of the intake pipes 33. This will prevent burning out of the bottom of the boiler shell 10, which would be an expensive replacement, while the upper fire tubes 18 of the boiler shell can be replaced quite readily, in the event that they are destroyed.

It will be noted that the lower header manifolds 26 are spaced a distance above the floor line on which the boiler is to be mounted, leaving a space 36 which allows easy access to the under-side of the headers 26, if it becomes necessary to replace worn or burned out tubes. Such construction is necessary in the event that the boilers are arranged in tandems, as illustrated in Figures 2 and 4.

Another form of my invention is illustrated in Figures 4 and 5, wherein the general boiler construction and the principal features of my invention are the same as those shown in Figures 1, 2 and 3, and indicated by the same numerals. The essential differences between this form and the preferred form of my invention, hereinabove described, are in the positioning of the water tubes. In the preferred form of my invention the water tubes are vertically disposed, which construction is desirable in the event that the boilers are located in a place having plenty of head room above the boiler but little or no room behind and in front of the boiler. In such a location the removal and changing of a water tube would necessitate it being drawn upwardly as there would be no room for a longitudinal movement of the tube. In another form of my invention illustrated in Figures 4 and 5, which I am about to describe, the water tubes are vertically disposed along the sides but cross over each other and such an installation is made when there may be little head room above the boiler but plenty of room on the sides because in the event that it is necessary to replace a leaky water tube it must be withdrawn sidewise. In this type of construction the burning fuel does not have direct access to the outer shell of the boiler which is protected by a suitable layer of heat insulating material over the tops of the crossed tubes. This feature is desirable, especially in high pressure boilers.

I have differentiated the water tubes and auxiliary parts of this form of the invention from the preferred form by subscribing a

prime after each of the parts of the modified form which correspond with like parts in the preferred form but are slightly different in shape and position. The vertically disposed water tubes 25', located along the side walls of the combustion chamber 15, are shaped so that each alternately crosses the other at a point below the bottom of the boiler shell 10 substantially near the top of the combustion chamber 15. Thus we have the water taken in by the pipes 33 (Figure 4) conducted downwardly through pipes 34' to the lower headers 26' on the opposite sides of the boiler, and as the heated water rises in the water tubes 25', it enters the upper headers 27' which are located on the converse sides of the combustion chamber 15, and is discharged into the shell 10 through pipes 35'. The network of tubes 25' forms a shallow V-shaped top where they cross, as seen in Figure 4, and a lining of fire-brick clay or some similar substance is formed along this shallow V top channel and is indicated by the numeral 38. The only difference this construction makes in the circulation of the water in the boiler is that the intake water is drawn from the passage 30 on one side of the boiler through the intake pipe 33 and the steam and heated water is discharged into the boiler shell 10 on the opposite side. The flames and burning fuel in the combustion chamber do not heat the bottom of the boiler shell 10 in this form of the invention but pass to the rear portion of the boiler, through the fire chamber 17, and thence forwardly through the fire tubes 18, smoke-box 19, and are exhausted upwardly through the smoke-stack 20. Extra water tubes 25'' are connected by suitable upper and lower headers along the rear wall of the combustion chamber in series with the water tubes 25', and serve the same purpose in the same manner as the water tubes 25' along the side walls.

In Figures 6 and 7, I illustrate another modified form of my invention, embodying the same principles, features and advantages as the two forms just described, and using the same numerals to designate the parts which correspond with the parts disclosed in the preferred form of my invention, illustrated in Figures 1 and 2. In this form, the parts that make up the water-tube section of the boiler are also in a different position and shaped in a different manner from the preferred form but perform the same functions and are for the same purpose. This form of the invention is desirable when the head room or space above the boiler is limited and there is plenty of room in the rear and in front of the boiler. Thus, in the removal of a leaky water tube, it can be drawn through the forward or rearward end and thus be easily replaced. The parts are differentiated in this form by the subscription of the letter "a" after each corresponding numeral. The

under shell of the boiler 10 is heated by the burning fuel in the combustion chamber 15 which passes through the fire chamber 17 to the fire tubes 18 of the boiler and out through the smoke-box 19 and smoke-stack 20. The water tubes 25^a are substantially horizontally disposed along the side walls of the combustion chamber 17 at a slight angle, and the upper header 27^a, which is connected with the discharge outlet pipe 35^a, is located on one end of the boiler, shown in Figure 6 at the forward end, and the header manifold 26^a, which receives the cooling water from the boiler through the intake pipes 33 and 34^a, is located at the rear part of the boiler. The water is drawn in through the intake pipe 33, located between the circulating plates 31 at the rear of the boiler, through 34^a into the manifold headers 26^a, and as it is heated, rises through the water tubes 25^a to the forward header 27^a, whence it is discharged into the opposite or forward end of the boiler shell 10. The other side of the boiler has the converse of this arrangement; that is, the lower intake header 26^a is located at the forward end of the boiler and the intake pipe 33, for this side is located at the forward end of the boiler, while the discharge header 27^a, which is connected with the outlet discharge pipe 35^a, is located at the rear part of the boiler but functions in the same manner as the one on the opposite side of the boiler.

In this form of the invention, the water to be fed to the water tubes on one side of the boiler is taken in at the rear of the boiler substantially at the horizontal center line and discharged back into the boiler at the forward end of this same side substantially at the water level of the boiler shell, and the water on the opposite side of the boiler is taken in at the front end of the boiler and discharged back into the rear part of the boiler on the same side.

I claim:

1. The combination in a boiler of a boiler shell, fire tubes therefor grouped to leave a vertically, longitudinally extending space for downflowing water, a combustion chamber therebeneath, water tubes in the combustion chamber, and means affording water flow from the shell to the water tubes and communicating with the shell at a point which is above that area of the shell directly exposed to the combustion chamber, and which is in said space, thereby longitudinally to distribute the down draft of the water.

2. The combination in a boiler of a boiler shell, fire tubes therefor grouped to leave a vertically, longitudinally extending space for downflowing water, a combustion chamber therebeneath, water tubes in the combustion chamber, means affording water flow from the shell to the water tubes and communicating with the shell at a point which

is above that area of the shell directly exposed to the combustion chamber and which is in said space, thereby longitudinally to distribute the down draft of the water, and 5 means affording water flow from the water tubes to the shell and communicating with the shell at the upper part thereof.

3. The combination in a boiler of a boiler shell, fire tubes therefor grouped to leave a vertically, longitudinally extending space 10 for downflowing water, a combustion chamber, water tubes in the combustion chamber, and means affording water flow from the shell to the water tubes comprising feed tubes 15 positioned in the space of the downflowing water in the boiler, which tubes extend up to substantially the horizontal plane of the axis of the shell, connecting tubes communicating with the lower ends of the water tubes and said feed tubes to conduct the 20 water from the boiler shell to the water tubes.

4. The combination in a boiler of a boiler shell, fire tubes therefor grouped to leave a vertically, longitudinally extending space for 25 downflowing water, a combustion chamber, water tubes in the combustion chamber, means affording water flow from the shell to the water tubes comprising feed tubes positioned in the space of the downflowing water in the boiler, which tubes extend up to substantially the horizontal plane of the axis of the boiler, connecting tubes communicating with the lower ends of the water tubes and said feed tubes to conduct the water 30 from the boiler shell to the water tubes, and means affording water flow from the water tubes to the shell comprising discharge tubes 35 communicating with the water tubes and the shell at a point above the water level in the shell.

5. The combination in a boiler of a boiler shell having horizontally disposed fire tubes therefor arranged in vertical tiers with spaces between certain of the tiers for downflowing water, a combustion chamber therebeneath, 45 a plurality of water tubes spaced along the walls of the combustion chamber, and means communicating with the water tubes and shell to deliver downflowing water from the spaces between the tiers of fire tubes in the shell to the water tubes from a point in the shell which is above that area of the shell directly exposed to the combustion chamber.

6. The combination in a boiler of a boiler shell, fire tubes therefor grouped to leave a vertically, longitudinally extending space, a pair of spaced, vertical, circulating plates disposed within the spaces to provide for the downward flow of water therebetween, a combustion chamber beneath the shell, water tubes in the combustion chamber, and means affording water flow from the shell to the water tubes comprising vertically disposed tubes between the pair of circulating plates 60 in the shell adapted to receive downflowing 65

water at a point above the area of the shell directly exposed to the combustion chamber and communicating tubes associated therewith and connected with the water tubes.

7. The combination in a boiler of a boiler shell, fire tubes therein arranged in groups with vertical spaces therebetween, pairs of spaced, vertical, circulating plates disposed in the spaces for providing for the downward flow of the cooling water therebetween, a combustion chamber therebeneath, a plurality of water tubes spaced along the walls of the combustion chamber, means to feed the downward flowing, cooling water from the boiler shell to the water tubes comprising vertically disposed intake feed pipes located between the pairs of circulating plates in the shell extending upwardly therein to a point which is above that area of the shell directly exposed to the combustion chamber, thereby to receive downflowing water from the space extending longitudinally between the circulating plates, and communicating with the water tubes to afford water flow from the shell to the water tubes.

In witness whereof, I hereunto subscribe my name this 8th day of March, 1928.

PAUL G. KAISER.
